UNITED STATES PATENT OFFICE.

RICHARD TRÖGER, OF CHARLOTTENBURG, GERMANY, ASSIGNOR TO GENERAL ELECTRIC COMPANY, A CORPORATION OF NEW YORK.

MEANS FOR REGULATING CENTRIFUGAL COMPRESSORS

1,041,529.

Specification of Letters Patent. Patented Oct. 15, 1912.

Application filed February 16, 1912. Serial No. 678,923.

To all whom it may concern:

Be it known that I, RICHARD TRÖGER, a subject of the King of Prussia, residing at Charlottenburg, Germany, have invented certain new and useful Improvements in Means for Regulating Centrifugal Compressors, of which the following is a specification.

In the operation of centrifugal air compressors when the load is decreased to a small percentage of the total, a peculiar action known as surging or pumping takes place, meaning thereby that the air surges to and fro in the compressor and in the piping connected thereto. For the purpose of this case it is sufficient to say that surging is highly objectionable as it causes excessive vibration and noise, interferes with the operation of the apparatus supplied with air, and decreases the economy of operation. It has been proposed to prevent surging by placing a blow-off valve in the discharge conduit that is set to open automatically when the volume of air discharged by the compressor reaches a certain relatively small value, said valve operating in response to a pressure difference existing between two points in the discharge conduit. Since the valve always opens when the load decreases to said predetermined low or critical value, it follows that as the load is further decreased the energy required to drive the compressor will remain the same, because the amount of air passing through the compressor will remain the same, but the amount of air discharged or escaping through the valve will, however, increase as the load decreases. In other words, these compressors are inefficient and wasteful at light loads.

The present invention has for its object to provide an improved governing or regulating mechanism for compressors, whereby their effective and efficient range of operation can be increased, especially at light loads, and the losses decreased.

In carrying out my invention a blow-off valve is placed in the discharge conduit of the compressor but instead of being responsive to a pressure difference existing on the discharge side of the compressor as heretofore, it is responsive to a pressure difference existing on the inlet side. This pressure difference is obtained through the use of a suitable device such as Venturi tube, one side

of the valve actuator being subjected to the throat pressure and the other to that existing at the discharge end of the tube. Back of the Venturi tube proper or in the inlet pipe is located a throttle valve that may be moved by hand or automatically to vary the admission of air to the compressor. Since the air must first be acted upon by the valve before it enters the Venturi tube, it follows that said pressure difference due to the action of the tube must bear a definite relation to the volume of air passing into the compressor. By means of the throttle valve, I can vary the output of the compressor over wide limits, and at the same time the critical point of opening of the blow-off valve will be lowered as the load is decreased thereby, decreasing the losses heretofore mentioned. To state the matter another way, my invention comprises the feature that the pressure difference acting upon the blow-off valve is obtained from the part of the suction conduit of the compressor which follows a throttling member, so that the pressure difference which is critical for the opening of the blow-off valve is made to depend upon the suction pressure as regulated by the throttling member.

In the accompanying drawing, which illustrates one of the embodiments of my invention, is shown a multistage centrifugal air compressor and the regulating mechanism therefor.

1 indicates a multistage centrifugal air compressor of any suitable type. It is driven by a motor 2 shown in dotted lines, which may be an electric motor, a steam turbine, or other engine. The compressor is provided with an inlet conduit 3 and a discharge conduit 4. Located in the inlet conduit is a Venturi tube 5. At the throat 6 of the tube is a series of holes that open into an annular chamber 7 surrounding the throat. To this chamber is connected a pipe 8 that leads to the motor for actuating the blow-off valve as will appear later. 9 indicates a pipe connected to the inlet conduit at or about the discharge end of the tube. This also conveys fluid under pressure to the motor for actuating the blow-off valve. Between the throat 6 and the end of the tube a pressure difference exists when air or other fluid is flowing through the inlet conduit. This pressure difference will depend upon the amount of fluid flowing, it

being greater as the amount of fluid increases. The pressure existing at the throat 6 will be less than that existing at the discharge end of the tube.

5 Mounted either in one end of the Venturi tube or in the inlet conduit 3 is a throttle valve 10, by means of which the supply of air for the compressor may be controlled. This valve is provided with a stem having a gear 11 on the upper end that meshes with a pinion 12 mounted on the lower end of an actuating shaft, the latter being provided with a hand-wheel 13. By rotating the hand-wheel in one direction or the other, the throttling effect of the valve 10 can be adjusted.

10 The construction and arrangement of the blow-off valve will now be described: Connected to the discharge conduit 4 or formed integral therewith is a cylinder 14 containing a piston valve 15, the latter being arranged to move up and down to cover and uncover the discharge ports 16 shown in dotted lines. The valve is actuated by a piston 17 located in the enlarged cylinder 18. Between the upper side of the piston and the head of the cylinder is located a compression spring 19 that normally tends to push the valve 15 downward and open the ports 16 and permit air to escape. This tendency is opposed by the pressure difference created by the device located in the inlet conduit, *i. e.*, the Venturi tube.

15 In order to balance the pressures on opposite sides of the valve 15, a bypass 20 is provided that connects the conduit 4 with the cylinder 14.

20 The fluid pressure above the piston 17 is less than the fluid pressure below it. So long as the compressor is working above a certain minimum load, the fluid pressure under the piston 17 will be sufficient to overcome the effect of the fluid pressure received from the pipe 8 and the force exerted by the spring 19, but when the load is decreased to such a low value that surging could take place, the pressure difference due to the Venturi tube decreases, so that the pressure of the spring 19 when added to that of the fluid received from the pipe 8 will be sufficient to open the valve 15, and discharge air through the ports 16. It will thus be seen that the valve 15 forms a means for insuring a certain minimum load for the compressor and its driving motor, which load is superior to that at which surging can take place. Furthermore, since the throttle valve precedes the device for creating pressure difference it follows that the latter is under the control of said valve. Such being the case, the blow-off valve instead of opening at all times under the same load conditions, will open at different load conditions depending upon the throttling effect of the valve 10. In other words, the range

of operation of the compressor can be increased by my improved arrangement, owing to the fact that the blow-off valve is not set for one fixed minimum load, but is set to operate at an infinite number of load values, depending upon the position of the throttle valve. 70

Assuming the compressor to be in service and that the consumption of compressed air decreases for any cause, the throttle valve being wide open. With the decrease in consumption, the pressure difference acting on the valve 15 correspondingly decreases and at a certain minimum work performance of the compressor, the blow-off valve will open and discharge air. The operator on observing this fact, can, by throttling the inlet conduit, reduce the work performance of the compressor within certain limits without, however, causing surging, and at the same time the further opening of the blow-off valve will be retarded depending upon the degree of throttling. 75 80 85

90 In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means. 95

What I claim as new and desire to secure by Letters Patent of the United States, is:—

1. In combination, a centrifugal compressor having an inlet and a discharge conduit, a blow-off valve for discharging fluid under pressure from the compressor, a throttle valve in the inlet, and a means located on the compressor side of the throttle and sensitive to a change in the rate of flow of fluid passing through it for actuating the blow-off valve. 100 105

2. In combination, a centrifugal compressor having an inlet and a discharge conduit, a blow-off valve in the discharge conduit, a means sensitive to a change in the rate of flow of fluid passing through the inlet for controlling the operation of the blow-off valve, and a member for throttling the passage of fluid prior to its entrance to the inlet and said means. 110 115

3. In combination, a centrifugal compressor having an inlet and a discharge conduit, a blow-off valve in the discharge conduit, a means located in the inlet for creating a pressure difference responsive to changes in the rate of flow of the fluid passing through the compressor, a means for actuating the blow-off valve that is responsive to said pressure difference, and a throttle valve that is located in the inlet and precedes the said means. 120 125

4. In combination, a centrifugal compressor having an inlet and a discharge conduit, a blow-off valve in the discharge 130

conduit, means tending at all times to open the valve, a pressure responsive motor that normally opposes said means, a device for creating a pressure difference that is located in the inlet conduit, conduit means for conveying said pressure difference to the motor, and a throttle valve that is located on the inlet side of said device.

5. In combination, a centrifugal compressor having an inlet and a discharge conduit, a blow-off valve in the discharge conduit, that is arranged to open when the load on the compressor falls below a certain value, a means actuated by fluid under pressure for holding the valve closed, a Venturi tube for creating a pressure difference, conduits conveying fluid under pressure from the tube to the said means, and a throttle

valve in the inlet conduit for controlling the amount of fluid that passes through said tube.

6. In combination, a centrifugal compressor having an inlet and a discharge conduit, a blow-off valve in the discharge conduit that opens under conditions of decreasing load, a Venturi tube in the inlet conduit for controlling the action of the valve, and a throttle valve that regulates the admission of fluid to said tube.

In witness whereof, I have hereunto set my hand this day of 26th January, 1912.

RICHARD TRÖGER.
